FLAT KNITTING FRAME

Herbert Dietrich, Meinersdorf i. E., Germany

Application November 2, 1937, Serial No. 172,438
In Germany November 3, 1936

6 Claims. (Cl. 66—89)

This invention relates to a flat knitting frame.

In order to produce a stocking having a French foot on a single flat knitting frame by simple means it has been proposed to equip the narrowing mechanism with only one narrower for each side of the fabric. These narrowers are applied in the usual manner to the leg and calf and also to the heel if the heel portions are worked on the same machine. Conditions differ, however, in the

5 toe which must have two narrowing zones on each side, and for this reason the narrowers of each fabric side are applied twice in each narrowing course and are correspondingly shifted between the two operations. In the toe, narrowing is car-

10 ried out by hanging first a few outer meshes inwardly to the extent of one needle, whereupon the narrower of each side is shifted and the meshes of the inner narrowing zone are also hung inwardly to the same extent together with the previously transferred meshes of the outer zones. The meshes of the outer zones are thus transferred twice in each course to attain the desired effect.

15 Although this mode of operation is not objectionable per se, it nevertheless involves certain drawbacks with respect to the machine. If the toe is narrowed in the manner described, it is necessary to use for each side of the fabric a narrower having a width equal to the combined width of the usual large and small narrowing fingers. This necessity counteracts the tendency to keep the spaces between the sinker heads or bars as narrow as possible, as the narrowers when not in use must be pushed sideways out of range 20 of the sinker heads, so that sufficient space for them must be provided. This drawback becomes particularly apparent if used legging machines are to be adapted to producing stockings in one operation. Such machines possess very narrow

25 narrowers, and the space assigned to them outside the sinker heads is therefore not large enough to accommodate narrowers having the width mentioned, unless they are swingably arranged, which in the interest of simplicity of construction is not desirable, however.

30 The invention overcomes these difficulties by racking the narrowers to the extent of their width after they have operated in the first zone, so that during the second narrowing operation only the meshes of the second zone are hung over.

35 The narrowers are thus not wider than a narrowing zone, and their lateral arrangement outside the sinker heads does not involve any troubles.

40 By way of example, the invention is illustrated

in the accompanying drawings, in which Figure 1 shows the working method of one narrower on each side of the fabric when the toe of a French foot is produced; Fig. 2 shows the parts for adjusting and limiting a narrower bar; Fig. 3 shows a device for operating the narrower; Fig. 4 shows means for operating the auxiliary stop; and Fig. 5 shows another possibility of narrowing in a French toe.

45 Referring to the drawings, in order to produce the toe of a French foot, as indicated in Fig. 1, the flat knitting frame is provided on each side of the fabric with only one narrower 3 which first hangs over the meshes of the inner zone 1 and then those of the adjacent zone 2. For this purpose, the narrower 3 of each side is approximately half as wide as the usual two narrowers combined and must be racked over its total width after it has carried out the hanging over operation in one zone. Furthermore, the narrowers 3 require accurate adjustment after racking, which is effected by the stops 9 operating on a screw spindle and provided with auxiliary stops 7 in known manner. The auxiliary stops adjust the narrowers 3 during covering of the inner zones, 50 and the stops 9 effect adjustment for the outer zones. Fig. 2 shows the stops of the left-hand narrowers 3 of the narrowing mechanism, it being assumed that the narrowers 3 of which only one is shown operate in the inner zone 1. The auxiliary stop 7 is therefore in operating position and movably secured to the nut member 8 of the stop 9. For the narrowing operation in the outer zone the stop 7 is swung out, so that the bar 10 carrying the narrowers 3 can be adjusted by the stop 9. The stop 7 can be controlled by a pattern mechanism.

55 Racking of the bar 10 and of the bar running in opposite direction, which is not shown, is preferably effected as for instance in clock attachments by a special lifting means which permits swinging in of the auxiliary stop 7. As shown in the drawings, this lifting means comprises an eccentric 12 arranged on the main shaft 11 and provided with a rotatable disc 13, a roller lever 14 movably disposed at 15, and a rope 17 passing over the guide pulley 16 which engages the bar 10 at 18. When the roll of the lever 14 is lifted by the eccentric 12, the bar 10 is displaced to the right and the auxiliary stop 7 can be brought into operative position, the arrangement being such that the roll of the lever 14 descends from the elevation of the eccentric 12 when the stop 7 is swung in and the bar 10 can engage the stop 7 by means of the usual tension medium. In the construction

shown the tension medium consists of a weight 19, which by means of the rope 20 and the guide 21 engages the bar 10 at 22. The use of a weight pull is advisable, as the racking of the narrowers 3 is quite large and would result in appreciable variations in power if ordinary tension springs were used. For the bar supporting the narrowers of the other side of the fabric an additional rope is connected with the weight 19 and the roller lever 14, the ropes being connected with the second bar by corresponding reversion of the roll. It is possible of course to provide for each bar a separate lifting device 11-18 and also a separate traction device 19-21.

15 The machine according to the invention can be used for both narrowing and widening in two zones, widening being required in stockings worked in one operation with widened heel portions. In the production of a French toe a blade 23 of known type is employed in the usual manner.

16 The device for operating the auxiliary stops 7 is known per se and comprises a downwardly extending arm 24 which is actuated by the spring 25. This spring 25 tends to move the auxiliary stop 7 in the direction of the arrow into an inoperative position. The auxiliary stop 7 is brought into its operative position by means of a pattern mechanism, which consists of the wheel 27 and the pattern chain 26 with the cam 28, and which operates the arm 24. The arrangement is such that the auxiliary stop 7 is brought into the operative position when a cam 28 of the pattern chain 26 is moved under the arm 24.

17 A flat knitting frame according to the invention can further be used for narrowing in two zones if the two zones on a side of a fabric differ in width. The structure shown in Fig. 3 indicates the production of a French toe. The inner zones 1 are the narrower ones, and the width of the narrowers 3 corresponds to the width thereof. Narrowing is first carried out in the inner zones 1, and the picked up meshes are hung over one needle inwardly in the usual manner, as shown. The narrowers 3 are then racked outwardly to the extent of their width, so that they are positioned at x in the outer zones 2 the meshes of which are hung inwardly over two needles. After this operation, the narrowers 3 are racked again outwardly to the extent of their width so as to occupy the position y at which they hang the remaining portion of the meshes of the zones 2 inwardly. The meshes of the zones 2 are thus hung inwardly in two operations whilst the formation of an additional narrowing line is avoided. In the construction shown the narrowers 3 are approximately one-third as wide as the usual two large and small narrowing fingers on one side together. The toe produced is practically equal to a French toe of the usual kind.

18 I claim:

1. A flat knitting frame, comprising means for narrowing and widening in a plurality of zones with the aid of one narrower on each side of the

goods, said narrowers operating a plurality of times in each course and having the width of the inner zones of their sides of the goods, said narrowers hanging over first the meshes of the inner zones and then being racked outwardly 5 for subsequent operation in the same row.

2. A flat knitting frame according to claim 1; wherein for narrowing French toes the narrower on each side of the goods is only approximately 10 half as wide as the usual two narrowing fingers on each side taken together and narrowing is carried out first in the inner zone.

3. A flat knitting frame according to claim 1, wherein for narrowing French toes the narrower on each side of the goods is only approximately 15 half as wide as the usual two narrowing fingers on each side taken together and narrowing is carried out first in the inner zone, and wherein stops operating on a screw spindle adjust the racking path of the narrowers from one zone 20 to the other and auxiliary stops adjust the narrowers during narrowing of the inner zones.

4. A flat knitting frame according to claim 1, wherein for narrowing French toes the narrower on each side of the goods is only approximately 25 half as wide as the usual two narrowing fingers on each side taken together and narrowing is carried out first in the inner zone, and wherein stops operating on a screw spindle adjust the racking path of the narrowers from one zone to 30 the other and auxiliary stops adjust the narrowers during narrowing of the inner zones, said auxiliary stops being movably secured to the first stops and controlled by a pattern mechanism.

5. A flat knitting frame according to claim 1, 35 wherein for narrowing French toes the narrower on each side of the goods is only approximately half as wide as the usual two narrowing fingers on each side taken together and narrowing is carried out first in the inner zone, and wherein 40 stops operating on a screw spindle adjust the racking of the narrowers from one zone to the other and auxiliary stops adjust the narrowers during narrowing of the inner zone, and wherein 45 bars for carrying the narrowers and lifting means for driving the bars inwardly are provided to place the auxiliary stops in operating position.

6. A flat knitting frame according to claim 1, wherein for narrowing French toes the narrower on each side of the goods is only approximately 50 half as wide as the usual two narrowing fingers on each side taken together and narrowing is carried out first in the inner zone, and wherein stops operating on a screw spindle adjust the racking of the narrowers from one zone to the 55 other and auxiliary stops adjust the narrowers during narrowing of the inner zone, and wherein bars for carrying the narrowers and lifting means for driving the bars inwardly to place the auxiliary stops in operating position are provided, 60 said lifting means comprising weights for drawing the bars toward the stops.

HERBERT DIETRICH.
